DESIGN FOR AN AIRPLANE

Irving Rogers, Monticello, N. Y.

Application September 18, 1946, Serial No. 133,387

Term of patent 14 years

(Cl. D71—1)

To all whom it may concern:

Be it known that I, Irving Rogers, a citizen of the United States of America and a resident of Monticello, in the county of Sullivan and State of New York, have invented a new, original and ornamental Design for Airplane, of which the following is a specification, reference being had to the accompanying drawing, forming part thereof, in which—

Fig. 1 is a side elevational view of an airplane embodying my new design.

Fig. 2 is a top plan view thereof.

Fig. 3 is a front elevational view.

I claim:

The ornamental design for an airplane, as shown.

IRVING ROGERS.
